[57] CLAIM

The ornamental design for a storage cabinet for compact discs, as shown and described.

DESCRIPTION

FIG. 1 is a front elevational view of a storage cabinet for compact discs showing our new design;

FIG. 2 is a front elevational view thereof, being shown with the front cover in a lowered position;

FIG. 3 is a left side elevational view of FIG. 1;

FIG. 4 is a right side elevational view of FIG. 2;

FIG. 5 is a bottom plan view of FIG. 1;

FIG. 6 is a rear elevational view of FIG. 1;

FIG. 7 is a top plan view of FIG. 1;

FIG. 8 is a top plan view of FIG. 2;

FIG. 9 is a front elevational view of FIG. 1; and,

FIG. 10 is a rear perspective view of FIG. 1.

FIG. 1.

FIG. 2.

FIG. 3.

FIG. 4.

FIG. 6.

FIG. 5.

FIG. 7.

FIG. 8.

FIG. 9.

FIG. 10.
